H. C. SCHROEDER.
COMPENSATING PUMP FOR PNEUMATIC VEHICLE TIRES.
APPLICATION FILED JUNE 20, 1918.

1,311,533.

Patented July 29, 1919.

Inventor.
Harry C. Schroeder

UNITED STATES PATENT OFFICE.

HARRY C. SCHROEDER, OF BERKELEY, CALIFORNIA.

COMPENSATING PUMP FOR PNEUMATIC VEHICLE-TIRES.

1,311,533.

Specification of Letters Patent. Patented July 29, 1919.

Application filed June 20, 1918. Serial No. 240,932.

To all whom it may concern:

Be it known that I, HARRY C. SCHROEDER, citizen of the United States, residing at Berkeley, in the county of Alameda and 5 State of California, have invented certain new and useful Improvements in Compensating Pumps for Pneumatic Vehicle-Tires, of which the following is a specification.

My invention is a compensating pump for 10 pneumatic vehicle tires and is an improvement on my pump disclosed in my application Serial No. 210,193, filed January 3, 1918.

The invention will be hereinafter fully 15 set forth and particularly pointed out in the claims.

Referring to the drawing, in which the 20 reference characters correspond to and indicate the same parts as those of the specification:

Figure 1 is a longitudinal section of one form of my improved pump.

Fig. 2 is a longitudinal section of another form of my improved pump.

25 In the drawing 1 indicates the valve of a pneumatic tire and 2 the cap therefor. The cap is formed with an internally threaded cap 3 which screws on the outer end of the valve 1, and with an external 30 thread 4 on its inner end on which a nut 5 screws against the felly of the wheel on which the tire is mounted. The cap is formed with a partition 6 adjacent the cap 3 and with a partition 7 intermediate the 35 partition 6 and the head of the cap. The partition 7 dividing the cap into a chamber 8 and the partitions 7 and 6 dividing the cap into a chamber 9. The partition 7 is provided with a port 10 extending transversely 40 therethrough, which port establishes communication between the chambers 8 and 9. A rubber sack 11 extends through the port 10 into the chambers 8 and 9 and is cemented to the walls of the chamber 8 while 45 it is free to expand and contract within the chamber 9, the partition 7 dividing the sack into two chambers 12 and 13 respectively within the cap chambers 8 and 9 and the port 10 providing for a port 14 establishing 50 communication between the chambers 12 and 13. A liquid such as mercury is placed within the sack which occupies about half of the expanded sack.

55 In the form of my invention shown in Fig. 1, the cap 2 is provided with air inlet ports 15 and the chamber 9 is provided with an

air inlet port 16 extending through partition 6. A check valve 17 is arranged within the port 16 to permit air to enter the chamber 9 and to prevent air from escaping from 60 said chamber through port 16. An air outlet port 18 is provided for the chamber 9 which extends through partition 6 into the head of screw cap 3 and communicates with the valve 1. A check valve 19 is arranged 65 within the port 18 to permit air to pass through the port into the valve 1 and to prevent air from escaping from valve 1 and entering chamber 9.

In the form of my invention shown in Fig. 70 2, the sack 11 is cemented to the walls of the cap chamber 9. A pouch 20 forming an air chamber is located in the end of the sack chamber 13 adjacent the partition 6 and a tube 21 extends through the sack and the 75 partition from the pouch to the screw cap 3. A check valve is arranged within the tube 22 which opens to permit air to pass from the pouch into the cap 3 and into the valve 1. The partition 6 is provided with an air 80 inlet port 23 communicating with port 21 and a check valve 24 is located therein to admit air through port 21 into pouch 20 and to prevent air passing from the pouch into the atmosphere. 85

In the form of my invention shown in Fig. 1, the air enters the chamber 9 through ports 15 and 16 and pressing against the end of sack chamber 13 forces the mercury in the sack up into the vacuum in the sack chamber 90 12. As the wheel rotates the mercury is forced into sack chamber 13 by centrifugal force, which forms a liquid piston compressing the air in chamber 9 and closing the valve 17 and preventing the escape of air 95 from the chamber 9 through port 16, but the air is not compressed sufficiently to open valves 19 and 1. When the wheel strikes a rough place in the road the reaction of the impact forces the mercury farther into the 100 sack chamber 13 which compresses the air in chamber 9 until it opens the valves 19 and 1, and forces the air through port 18 and valve 1 into the tire.

In the form of my invention shown in Fig. 105 2, the air normally entering the pouch 20 through ports 23 and 21 fills the pouch and forces the mercury upwardly into the sack chamber 12. As the wheel rotates more mercury is forced into sack chamber 13 by centrifugal force compressing the pouch 20 but not sufficiently to open valves 22 and 1. When 110

the wheel strikes a rough place in the road the reaction of the impact forces the mercury farther into the sack chamber 18 which compresses the air in the pouch 20 until it 5 opens valves 22 and 1 and forces the air through port 21 and the valve 1 into the tire.

Having described my invention, I claim as new and desire to secure by Letters 10 Patent:

1. In combination with a pneumatic tire valve, a compensating air pump provided with a flexible piston operatable by centrifugal force and vibration. 15
2. In combination with a pneumatic tire valve, a cap for said valve, and a compensating air pump arranged in said cap and provided with a flexible piston operatable by centrifugal force and vibration. 20
3. In combination with a tire valve, a cap for said valve, said cap being formed with a pump chamber, an elastic sack arranged in said chamber, air inlet and outlet means for said chamber, said outlet means communicating with said tire valve, and means for permitting a liquid to flow in said sack to compress the air in said pump chamber into said tire valve. 25
4. In combination with a tire valve, a cap for the valve, an air chamber in said cap, means for admitting air into said chamber and means for permitting the air to pass from said chamber into said valve, and a liquid piston for acting upon the air in said air chamber. 30
5. In combination with a tire valve, a cap for the valve, an air pump arranged within said cap for pumping air into said tire valve, said air pump including a liquid piston. 35
6. In combination with a tire valve, a cap for the valve, an elastic sack arranged within said cap, said sack being divided into two intercommunicating chambers, a liquid in said sack, one of said chambers forming a vacuum chamber and the other chamber 40 forming a piston, an air chamber, means for admitting air into said air chamber, and means for permitting air to be forced therefrom into said tire valve under the influence of said piston. 45
7. In combination with a tire valve, a cap for the valve, a sack arranged within said cap, a liquid in said sack, said sack being divided into two intercommunicating chambers forming a vacuum chamber and a piston, one of said chambers being secured to the wall of the cap, an air chamber in said cap, the other sack chamber and piston being loosely arranged and movable in said air chamber, and means for admitting air 50 into said air chamber and permitting air to be pumped therefrom under the influence of said piston. 55
8. In combination with a pneumatic tire valve and a cap therefor, a tire pump arranged in said cap and provided with a flexible piston, and means whereby said pump is connected to the valve stem of a tire. 60

In testimony whereof I affix my signature. 70

HARRY C. SCHROEDER.
